US00D494962S1

(12) United States Design Patent (10) Patent No.: US D494,962 S
Shen (45) Date of Patent: * Aug. 24, 2004

(54) HANDS FREE KIT

(76) Inventor: Ming-Ying Shen, 8F, No. 196-8, Sec. 3, Tatung Rd., Shijr, Taipei Hsien (TW)

() Term: 14 Years

(21) Appl. No.: 29/169,909

(22) Filed: Oct. 29, 2002

(51) LOC (7) Cl. 14-03

(52) U.S. Cl. D14/253; D14/243

(58) Field of Search D14/137, 138, D14/218, 147-148, 243, 247-248, 253, 144, 155, 159, 341-347, 358, 188, 192-198, 205, 206, 223, 225, 226, 228; 379/433.01-433.13, 419, 434, 428.01-428.04, 420.01-420.04, 440, 430; 455/550.1-90.3; D21/517; D3/208, 218; D10/104, 106
